UNITED STATES PATENT OFFICE.

FREDERICK W. MELLARS, OF SAN FRANCISCO, CALIFORNIA.

ADJUSTABLE WRENCH.

1,355,496.

Specification of Letters Patent.

Patented Oct. 12, 1920.

Application filed May 8, 1919. Serial No. 296,642.

To all whom it may concern:

Be it known that I, FREDERICK W. MELLARS, a citizen of the United States, residing in the city and county of San Francisco and 5 State of California, have invented certain new and useful Improvements in Adjustable Wrenches, of which the following is a specification.

My invention relates to improvements in 10 adjustable wrenches wherein a pivotally mounted handle operates in conjunction with a fixed jaw to move a movable jaw relatively thereto; and the objects of my invention are:

15 First, to provide an improved adjustable wrench;

Second, to provide an improved adjustable wrench adapted to be actuated to tightly engage a nut or the like to facilitate 20 the turning of said nut;

Third, to provide an improved device of 25 the character described wherein the handle is adapted to actuate the jaws of the wrench to rigidly and tightly engage a nut or the like;

Fourth, to provide an improved adjustable wrench adapted to utilize the first portion of the movement of the handle thereof to rigidly engage a nut or the like and to 30 turn said nut or other object during the remaining portion of the said movement;

Fifth, to provide an improved wrench of 35 the type set forth that shall be adapted, by merely reversing the position of the wrench, to tighten or loosen a nut on a bolt, or a similar operation; and

Sixth, to provide an improved wrench having improved means whereby the jaws thereof may be easily and readily adjusted 40 to various sizes of nuts, rods or the like.

I accomplish these several objects by means of the device disclosed in the drawings, forming a part of the present specification and drawings, and in which:

45 Figure 1 is a broken elevation, partly in section, disclosing the mechanism of my improved adjustable wrench;

Fig. 2 is a side view of the wrench; and

Fig. 3 is a view similar to Fig. 1 but disclosing the mechanism in a different position.

Referring to the drawings the numeral 1 is used to designate in general a body portion having a fixed jaw 2 thereon, and oppositely positioned internal tongues 3 arranged laterally to said jaw 2, said tongues 3 being

arranged to slidably engage grooves 4 within opposite faces of a movable jaw 6 whereby said movable jaw 6 may be actuated to move relatively to the fixed jaw 2 on the body 1.

A toothed segment 7 is pivotally mounted upon a pin 8 secured to the body 1 and is provided with an extension or lug 9. Links 11 are pivotally connected to the end of the extension or lug 9 and to a similar lug 12 on the body of the movable jaw 6 as disclosed in Figs. 1 and 3 of the drawings.

A suitable operating handle 14 is bifurcated at one end to pivotally engage opposite ends of the pin 8 and on opposite sides of the body 1.

A spring controlled pawl 16 is slidably mounted within the handle 14 and is provided with a thumb piece 17 which extends beyond a slot 18 in the handle 14 and adjacent the pawl 16 slidably mounted thereon.

The tension of the spring 19 normally retains the pawl 16 in engaging relation with the toothed segment 7.

The combination of the handle 14, pawl 16 and toothed segment 7 comprises an adjustable means for adjusting the space between the fixed and movable jaws 2 and 6 respectively regardless of the relative position of said handle 14 to the fixed jaw 2.

In operation the pawl 16 is moved into engagement with one extremity of the segment 7 which will position the movable jaw 6 at its greatest distance from the fixed jaw 2 as disclosed in Fig. 1 of the drawings. By moving the handle 14 to the position indicated in dotted lines in Fig. 1 of the drawings the movable jaw 6 will be actuated to first rigidly engage a nut 20, or the like, which will then prevent farther movement of said movable jaw 6 relatively to the fixed jaw 2 consequently preventing farther movement of the said handle 14 relatively to the body 1 and fixed jaw 2 thereon. The wrench then becomes a rigid fixed tool and farther movement of the operating handle 14 will screw the nut 20, or other article to which it may be attached, on the bolt 21.

When the wrench has been thus turned as far as possible a reverse movement of the handle 14 will separate the movable and fixed jaws and thereby disengage the wrench from the nut 20 when a new engagement of the wrench with said nut 21 may be obtained.

To unscrew the nut 20 from the bolt 21 the entire wrench is turned over which ac-

tion will reverse the operation of said wrench.

To decrease or adjust the distance between the jaws to engage a smaller nut the handle 14 is moved to turn and thereby expose the other extremity of the toothed segment 7 and the pawl 16 is then disengaged from the toothed segment 7 and the handle is moved, without moving said segment 7, to register the pawl 16 with the desired notch or tooth of said segment, as for instance, as disclosed in Fig. 3 of the drawings.

In this manner the jaws are brought closer together and thereby easily and readily adjusted to the size of the nut or article to be screwed or unscrewed.

It is obvious that the range of sizes, or the adjustability of the space between the jaws 2 and 6 is only limited by the number of 20 teeth or notches on the toothed segment 7.

It is also obvious from the foregoing that I have provided an improved adjustable wrench having improved means for adjusting the jaws to the nut or article to be turned as well as improved actuating means for moving the jaws to grip the nut before pressure is brought to bear to rotate or turn said nut or other article.

Having thus described my invention, what 30 I claim as new and desire to secure by Letters Patent is:

1. An adjustable wrench comprising the combination with a fixed jaw of a movable jaw slidably connected to the fixed jaw and 35 adapted to operate in conjunction therewith; a toothed segment pivotally connected to the fixed jaw; links connecting the movable jaw with the segment; and means pivotally connected to the fixed jaw for engaging the segment to move the movable jaw relatively to the fixed jaw.

2. An adjustable wrench comprising the

combination with a fixed jaw of a movable jaw slidably connected to the fixed jaw and adapted to operate in conjunction therewith; 45 a toothed segment pivotally connected to the fixed jaw; links connecting the movable jaw with the segment; and a handle pivotally connected to the fixed jaw and adapted to engage the segment to move the movable jaw 50 relatively to the fixed jaw.

3. An adjustable wrench comprising the combination with a fixed jaw of a movable jaw slidably connected to the fixed jaw and adapted to operate in conjunction therewith; 55 a toothed segment pivotally connected to the fixed jaw; links connecting the movable jaw with the segment; a handle pivotally connected to the fixed jaw; and a pawl slidably mounted within the handle and arranged to engage the toothed segment to connect the handle thereto whereby the movable jaw may be moved relatively to the fixed jaw when said handle is moved relatively to said fixed jaw.

4. An adjustable wrench comprising the combination with a fixed jaw of a movable jaw slidably connected to the fixed jaw and adapted to operate in conjunction therewith; a toothed segment pivotally connected to the 70 fixed jaw; links connecting the movable jaw with the segment; a handle pivotally connected to the fixed jaw; a pawl slidably mounted within the handle and arranged to engage the toothed segment to connect the 75 handle thereto whereby the movable jaw may be moved relatively to the fixed jaw when said handle is moved relatively to said fixed jaw; and means for disengaging the pawl from the segment.

In witness whereof, I hereunto set my signature.

FREDERICK W. MELLARS.
